UNITED STATES PATENT OFFICE.

CHARLES D. ALLAN, OF CHICAGO, ILLINOIS, ASSIGNOR TO ALFRED L. FRITZSCHE, OF CLEVELAND, OHIO.

VALVE FOR FIRE EXTINGUISHER SYSTEMS.

Application filed August 23, 1915. Serial No. 46,956.

To all whom it may concern:

Be it known that I, CHARLES D. ALLAN, a citizen of the United States, and a resident of Chicago, in the county of Cook and 5 State of Illinois, have invented a certain new and useful Improvement in Fire Extinguishers, of which the following is a specification.

This invention relates to fire extinguishers and particularly to valves for automatic sprinkler systems of the general type known as air valves or dry-pipe valves.

One form of dry-pipe valve which has been used to a very large extent, is what is 15 known as a differential valve, in which a relatively small water admission opening is closed by a valve which is secured in closed position against a relatively high water pressure in the main or other source of supply of water under pressure, by a relatively large air valve which is exposed to an unbalanced, relatively low air pressure in the sprinkler system. As heretofore constructed, valves of this type have been objectionable for the reason that, when the valve 20 opens and water is admitted to the sprinkler system such water will form a water column, the pressure of which acting on the relatively large air valve, with the weight 25 of the valves, will, under certain conditions, cause said valves to become reseated and will prevent reopening thereof until the system has been drained.

This is known as "columning" and is such 30 a serious objection that it has been found necessary to provide supplementary mechanical means for its prevention, and various devices for this purpose have been designed and patented, but have met with only in- 40 different success.

The primary object of the present invention is to provide a construction for a dry-pipe valve of the differential type whereby "columning" will be prevented 45 without resort to mechanical means to prevent reseating of the air valve.

Further objects of the invention are to provide a dry-pipe valve which will be simple in construction, cheap to manufacture as compared with any dry-pipe valve of which I have any present knowledge; and which will be effective and reliable for its designed purpose.

To effect the foregoing objects, a dry- 55 pipe valve of my invention comprises the

various features, combinations of features and details of construction hereinafter described and claimed.

In the accompanying drawing in which my invention is fully illustrated, 60

Figure 1 is a central, vertical, sectional view of a dry-pipe valve embodying my invention, the valves being shown in closed position in full lines and in open position in dotted lines.

Figure 2 is a sectional, plan view on the line 2—2 of Fig. 1.

Figure 3 is a sectional elevation on the line 3—3 of Fig. 1; and

Figure 4 is a central, horizontal sectional view of a dry-pipe valve embodying my invention in somewhat modified form, showing the lower part of said valve.

Referring now particularly to Figs. 1 to 3 of the drawings, A designates the valve 75 casing which for convenience and economy of manufacture and to render the parts enclosed therein easily accessible, consists of a main section or body portion A', one side of which is closed by a removable side wall 80 A² secured to said body portion by cap screws or other suitable means, and formed on which is what may properly be designated a bonnet a. The position of the removable side A² relative to the body portion A' is accurately defined by dowel pins 85 a¹.

For reasons presently apparent, the closed side of the valve casing A opposite to the removable side A² thereof, comprises a central, substantially circular, off-set portion A³, which forms a corresponding recess on the inside of said casing.

The valve casing A is provided with a water admission opening 1 which is adapted 95 to be connected to a water main or other source of supply of water under pressure. As shown, said water admission opening opens laterally through the off-set portion A³ of the closed side of the valve casing A 100 and is substantially concentric therewith and also with the bonnet a formed on the removable side A² of said valve casing. At its upper end, said valve casing is provided with a discharge opening 2 which is adapted 105 to be connected with a sprinkler system.

Surrounding the water admission opening 1 within the valve casing is a valve seat 3 co-operating with which is a valve 4 provided with a surface 5 conforming to the 110

valve seat 3. A tight joint between the valve seat 3 and surface 5 can be formed by grinding the same together with emery flour or the like, in a familiar manner. In the 5 preferable construction shown, the valve seat 3 is formed at the end of what may be termed a nipple 6, which forms a tubular extension of the water admission opening 1 laterally into the recess in the casing A formed by the off-set portion A³ of said casing. Preferably, also, said nipple 6 is made 10 separate from the valve casing A and is detachably connected thereto by cap screws or the like, thus making provision for 15 finishing said nipples 6 and grinding the valve seats to a fit before they are placed into the casing A, and also for detaching and removing said nipples in case it becomes necessary, at any time, to regrind said valve 20 seat 3 and surface 5.

In order to centralize the surface 5 relative to the valve seat 3 when the valve 4 is subjected to pressure, as presently described, the valve seats 3 and 5 are correspondingly 25 inclined or beveled, forming what may be described as the curved surfaces of frustums of cones.

In operation, the valve 4 is adapted to be maintained closed against the force of the 30 water pressure in the main or other source of water supply by means of an air valve 7 which, in use, is subjected to an air pressure in the sprinkler system and is adapted to exert a pressure upon the valve 4 when in 35 closed position, the sizes of said air and water valves being such, respectively, that a relatively very low air pressure in the sprinkler system, operating on the air valve, will maintain the water valve closed against the 40 relatively high water pressure in the water main or other source of water supply sustained by the valve 4, all in a familiar manner.

Secured to the air valve 7 so as to form 45 a tight joint therewith is a flat ring 8 of suitable flexible material, as rubber, leather, or the like, which projects outwardly beyond the edge of the air valve 7 and over a valve seat 9 on the valve casing at the mouth of the recess formed by the offset portion A³ of the valve casing. As shown, the valve seat 9 is formed on a ring 10 secured in the mouth of said recess. In operation the rubber ring 8 is adapted to be held in close, air-tight contact with the valve seat 9 by the air pressure in the sprinkler system.

With the described construction, it is obvious that the air valve 7, when closed, will divide the interior of the casing A into a 60 compartment A⁴, which is in open communication with the sprinkler system, and a compartment A⁵ with which the admission opening 1 communicates directly.

To prevent corrosion of the valve seats 3 65 and 5, the valve 4 and nipple 6 are prefer-

ably made of brass or bronze and to prevent the rubber ring 8 from adhering to the valve seat 9, the ring 10 is preferably made of brass, bronze or block tin.

In the preferable construction shown in 70 Figs. 1 to 3, the water valve 4 and air valve 7 are formed integral with each other and are supported so as to be bodily movable towards and from their respective seats in the following manner:—Said valves are secured to the end of a valve stem 11 which has a bearing in a sleeve 12 supported by a spider 13 secured in the mouth of the bonnet a, and which is freely movable endwise 75 therein, the valve stem bearing in the sleeve 12 being in axial alignment with the water admission opening 1 and extending substantially horizontally, or at such inclination to the horizontal that said valves will not become reseated by gravity. With the described construction, it is obvious that, in the operation of the valve, a current of water entering the valve casing A through the water admission opening 1 will move both the water valve 4 and air valve 7 into 80 open position, indicated in dotted lines in Fig. 1, in which position they will remain until again reseated manually. That is, water entering said admission opening 1 will move both the water valve 4 and the air 85 valve 7 into stable open position.

When said valves are in closed position, the valve stem 11 should not touch the sides of the bearing in the sleeve 12, as such contact might interfere with perfect contact of the valve seats 3 and 5 of the water valve, and, by corrosion of said valve stem or of its bearing, interfere with the designed operation of said valves. To prevent such contact of the valve stem 11 with its bearing, 90 said valve stem is slightly tapered. As shown, said valve stem is thus tapered at its end remote from said valves for about 2/3 of its length, the remaining third of said valve stem adjacent to said valves being left 95 cylindrical.

To provide for conveniently reseating said valves when it is desired to reset said dry-pipe valve after having been operated, a hole 14 is formed in the outer end of the bonnet 115 a in axial alignment with the water admission opening 1 and the valve stem bearing in the sleeve 12, said hole being of sufficient size to permit a rod or the like to be inserted through said opening into contact with the 120 outer end of the valve stem 11 by means of which said valves may be pushed to their seats or, by making the hole 14 sufficiently large, said valves may be reseated by hand. The hole 14 is adapted to be closed by means 125 of a removable plug 15, the inner end of which terminates short of the end of the valve stem 11, when the valves 4 and 7 are in open position, and is preferably rounded to prevent a rod or bar from being secured 130

between the end of said valve stem, when the valves are in closed position, and the inner end of said plug, thereby locking said valves in closed position.

5 Due to the taper of the valve stem 11, the valves 4 and 7 will sag somewhat out of line with their seats on the nipple 6 and the ring 8. When, however, the air pressure is turned on to the sprinkler system, the pressure exerted thereby on the air valve 7, acting on the inclined valve seats 3 and 5 on the nipple 6 and valve 4, respectively, will operate, in an obvious manner, to perfectly centralize the inclined valve seats 3 and 5.

10 When said valves are in closed position, and the system is under air pressure, said valves 4 and 7 will be supported independently of the valve stem 11. Also, said valve stem, being rigidly secured in said valve structure, will, in turn, be supported thereby independently of and concentric with its bearing in the sleeve 12, whereby, due to the taper of said valve stem, it will not contact with its bearing at any point, in the manner desired.

Instead of forming the air and water valves integral with each other, as shown in Figs. 1 to 3 and heretofore described, my invention contemplates forming said valves 30 separate from each other, and movably securing said water valve to a rigid part of the valve casing or a support rigidly attached thereto, said water valve being preferably pivoted to said valve casing or 35 support, whereby water under pressure entering the valve casing through the water admission opening, will move said water valve into stable open position. Excepting for the proposed change in the water valve and 40 the manner of supporting and operating the same and for certain slight changes of construction incident thereto, a valve embodying my invention in said modified form will be in all respects similar in construction and 45 method of operation to the preferred form of valve shown in Figs. 1 to 3 and will be readily understood by persons familiar with this art from the drawings, particularly in view of the foregoing description of the 50 preferred form of valve shown in Figs. 1 to 3.

A valve of my invention embodying the foregoing modification is shown in Fig. 4 of the drawings and will now be described.

55 In said modification the water valve, designated 4' is hinged to the nipple 6' by means of a yoke 16, bolted or otherwise detachably connected to said valve 4', corresponding bosses being formed on said nipple 60 and yoke which are provided with aligned bearings to receive the hinge pin 17, and the bearing in one thereof being fitted loosely to provide for limited play of said valve 4' to permit the bearing surface 5' thereon to seat 65 itself accurately upon the valve seat 3'.

With the described construction, it is obvious, that, by disconnecting the yoke 16 from the valve 4', said valve will be free to turn on its longitudinal axis, thus providing for conveniently grinding the valve seats 3' 70 and 5' together.

In the preferable construction shown the hinge pin 17 extends substantially vertical so that water under pressure entering the admission opening 1' will move the water valve 4' to one side out of the current of water under pressure entering the valve casing through the water admission opening 1', in which position it will obviously remain until again seated by hand. I do not desire, however, to limit myself to this particular manner of pivoting the valve 4', as my invention contemplates varying the position of the hinge pin 17 from the vertical, the only limitation being that said valve shall be 85 maintained in stable open position by gravity.

In operation, the valve 4' is adapted to be maintained closed against the water pressure in the main or other source of water supply, by the air valve 7', a rigid part of which is adapted to bear upon the apex of the valve 4' when in closed position, said water valve being so shaped that when the air valve 7' is moved a sufficient distance 95 to permit the apex of said water valve to pass out of engagement therewith, all other parts of said water valve will swing clear of said air valve.

When said modified form of dry-pipe 100 valve is set for operation, the valve 4' and the air valve 7' will be in the positions shown in full lines, Fig. 4, in which position they will be maintained by the air pressure in the sprinkler system. When, however, one 105 of the sprinklers of the sprinkler system opens, thus venting said sprinkler system, the water pressure on the valve 4' will operate to move both said water valve 4' and the air valve 7' into open position, shown in 110 dotted lines in Fig. 4, in which positions both of said valves will be maintained by gravity entirely out of the water-way and in stable open positions so that accidental 115 reseating thereof will be absolutely impossible, and said valves can only be reset or reseated by hand.

Like the preferred form of the valve shown in Figs. 1 to 3, the valve casing of said modified form of valve is provided with 120 a water discharge opening formed in the top thereof. Said water discharge opening does not appear in said Fig. 4, however, for the reason that said Fig. 4 shows only the lower part of the valve. In practice, 125 however, any mechanic of ordinary skill in this art can readily supply said water discharge opening, particularly in view of the disclosure of Figs. 1 and 2 and the portions of the specification descriptive thereof. 130

In use, my improved valve will be provided with suitable drain connections, alarm devices and the like, these, however, can readily be supplied, by any person familiar with the construction and operation of such devices and need not, therefore, be described in detail and for that reason will not be shown in the drawings.

I claim:

1. In a dry-pipe valve, the combination of a valve casing provided with water admission and discharge openings, a valve adapted for closing said water admission opening, an air valve adapted for dividing the interior of said valve casing into separate compartments and for maintaining the water valve closed, and means for supporting and guiding said water and air valves, the relation being such that water under pressure entering said valve casing through the water admission opening will move said air and water valves into stable open position, the means for supporting and guiding said air valve comprising a valve stem secured to said air valve and a sleeve within the valve casing provided with a bearing for said valve stem, said valve stem and its bearing extending in such relation to the horizontal that when open said valve will not reseat by gravity, substantially as described.
2. In a dry-pipe valve, the combination of a valve casing provided with water admission and discharge openings, a valve adapted for closing said water admission opening, an air valve adapted for dividing the interior of said valve casing into separate compartments and for maintaining the water valve closed, said water and air valves forming a unitary structure, and means for movably supporting and guiding said valves comprising a valve stem secured thereto and a sleeve within the casing provided with a bearing for said valve stem, said valve stem and its bearing extending in such relation to the horizontal that when open said valves will not reseat by gravity, substantially as described.
3. In a dry-pipe valve, the combination of a valve casing provided with water admission and discharge openings, a valve adapted for closing said water admission opening, an air valve adapted for dividing the interior of said valve casing into separate compartments and for maintaining the water valve closed, said water and air valves forming a unitary structure, and means for movably supporting and guiding said valves comprising a valve stem secured thereto and a sleeve within the casing provided with a bearing for said valve stem, said valve stem and its bearing extending in such relation to the horizontal that when open said valves will not reseat by gravity, and the seat for said water valve being beveled, substantially as described.

4. In a dry-pipe valve, the combination of a valve casing provided with water admission and discharge openings, a valve adapted for closing said water admission opening, an air valve adapted for dividing the interior of said valve casing into separate compartments and for maintaining the water valve closed, said water and air valves forming a unitary structure, and means for movably supporting and guiding said valves comprising a valve stem secured thereto and a sleeve within the casing provided with a bearing for said valve stem, said valve stem and its bearing extending in such relation to the horizontal that when open said valves will not reseat by gravity, said valve stem being smaller than its bearing and the seat for said water valve being beveled, substantially as described.

5. In a dry-pipe valve, the combination of a valve casing provided with water admission and discharge openings, a valve adapted for closing said water admission opening, an air valve adapted for dividing the interior of said valve casing into separate compartments and for maintaining the water valve closed, said water and air valves forming a unitary structure, and means for movably supporting and guiding said valves comprising a valve stem secured thereto and a sleeve within the casing provided with a bearing for said valve stem, said valve stem and its bearing extending in such relation to the horizontal that when open said valves will not reseat by gravity, said valve stem being smaller than its bearing and being slightly tapered, and the seat for said water valve being tapered, substantially as described.

6. In a dry-pipe valve, the combination of a valve casing provided with water admission and discharge openings, a valve adapted for closing said water admission opening, an air valve adapted for dividing the interior of said valve casing into separate compartments and for maintaining the water valve closed, and means for movably supporting and guiding said water and air valves, the relation being such that water under pressure entering said valve casing through the water admission opening will move said valves into stable open position, the means for supporting and guiding said air valve comprising a valve stem secured to said air valve and a sleeve within the valve casing provided with a bearing for said valve stem, the axes of said valve stem and its bearing being substantially horizontal, substantially as described.

7. In a dry-pipe valve, the combination of a valve casing provided with water admission and discharge openings, a valve adapted for closing said water admission opening, an air valve adapted for dividing the interior of said valve casing into separate

- compartments and for maintaining the water valve closed, said water and air valves forming a unitary structure, and means for movably supporting and guiding said valves 5 comprising a valve stem secured thereto and a sleeve within the casing provided with a bearing for said valve stem, the axes of said valve stem and its bearing being substantially horizontal, substantially as described.
- 10 8. In a dry-pipe valve, the combination of a valve casing provided with water admission and discharge openings, a valve adapted for closing said water admission opening; an air valve adapted for dividing the interior 15 of said valve casing into separate compartments and for maintaining the water valve closed, said water and air valves forming a unitary structure, and means for movably supporting and guiding said valves 20 comprising a valve stem secured thereto and a sleeve within the casing provided with a bearing for said valve stem, said valve stem and its bearing extending in such relation to the horizontal that said valves will not reseat by gravity, said valve being smaller 25 than its bearing and the seat for said water valve being beveled and the seats for said water and air valves being substantially in the same plane at right angles to the axis 30 of the valve stem bearing, whereby adjustment of said water valve to its seat will impart a minimum lateral throw to the air valve and the valve stem, substantially as described.
- 35 9. In a dry-pipe valve, the combination of a valve casing provided in one of its sides with a water admission opening and the opposite side of which is removable and comprises a bonnet portion in alignment with 40 said admission opening, said valve casing also being provided with a discharge opening, a valve adapted for closing said water admission opening, an air valve adapted for dividing the interior of said valve casing 45 into separate compartments and for maintaining the water valve closed, and means for movably supporting and guiding said water and air valves, the relation being such that water under pressure entering said 50 valve casing through the water admission opening will move said water and air valves into stable open position, the means for sup-
- porting and guiding said air valve comprising a valve stem secured to said air valve and a sleeve supported in the mouth of the 55 bonnet portion of the removable side of said casing provided with a bearing for said valve stem, said valve stem and its bearing extending in such relation to the horizontal that when open said valve will not reseat by 60 gravity, substantially as described.
10. In a dry-pipe valve, the combination of a valve casing provided in one of its sides with a water admission opening and the opposite side of which is removable and comprises a bonnet portion in alignment with 65 said admission opening, said valve casing also being provided with a discharge opening, a valve adapted for closing said water admission opening, an air valve adapted for 70 dividing the interior of said valve casing into separate compartments and for maintaining the water valve closed, and means for movably supporting and guiding said water and air valves, the relation being such 75 that water under pressure entering said valve casing through the water admission opening will move said water and air valves into stable open position, the means for supporting and guiding said air valve comprising a valve stem secured to said air valve and a sleeve supported in the mouth of the 80 bonnet portion of the removable side of said casing provided with a bearing for said valve stem, said valve stem and its bearing 85 extending in such relation to the horizontal that when open said valve will not reseat by gravity, the bonnet portion of the removable side of said valve casing being provided with an opening in its outer end through 90 which the end of the valve stem will be accessible and may be subjected to pressure to force the air valve to its seat, and a removable plug for closing said opening, substantially as described. 95

In testimony that I claim the foregoing as my invention, I affix my signature in the presence of two subscribing witnesses this 20th day of August, 1915.

CHARLES D. ALLAN.
